UNITED STATES PATENT OFFICE.

CALVIN A. JONES, OF TRILBY, FLORIDA.

RAIL-ADJUSTER.

No. 850,652.

Specification of Letters Patent.

Patented April 16, 1907.

Application filed July 11, 1906. Serial No. 325,631.

To all whom it may concern:

Be it known that I, CALVIN A. JONES, a citizen of the United States of America, residing at Trilby, in the county of Pasco and State of Florida, have invented new and useful Improvements in Rail-Adjusters, of which the following is a specification.

The invention relates to an improvement in rail-adjusting means for use in connection with railroad-rails, comprehending specifically a means whereby a rail or a portion thereof may be adjusted to proper position without the necessity of disturbing the rail-securings means.

The rails of the track, particularly the guard-rails and inner rails of a curve, are frequently subjected to a displacement or leaning incident to the pressure of the truck-wheels, with the effect to increase the normal gage at these points and consequent liability of dangerous results.

It is the object of the present invention to obviate so far as possible the spreading tendency of the rails by bracing the tread portion of the rails, the construction further providing for adjusting said tread portion to correct incident displacement and restore the rail to normal gage.

The invention in the preferred details of construction will be described in the following specification, reference being had to the accompanying drawings, in which—

Figure 1 is a plan illustrating the application of my improved rail-adjuster. Fig. 2 is a vertical central section of the same. Fig. 3 is a sectional view showing a modified form of rail-block.

Referring particularly to the drawings, wherein like reference - numerals indicate like parts throughout the several views, my improved rail - adjuster comprises a rail-block 1, approximating in height the height of the rail and formed on the inner or rail proximate face to conform to the sectional contour of the rail.

In the preferred form illustrated in Figs. 1 and 2, wherein the adjuster is shown as primarily designed for coöperation with guard-rails 2, the rail-block is designed to bear at its lower end upon the outer base-flange of the rail, being shaped at the upper end to receive the rail-tread, the intermediate portion of the block fitting snugly against the web of the rail between the tread and base-flange.

The upper end of the block is formed with an inwardly-projecting lip 3, designed to par-

tially overlie and rest upon the tread-surface of the rail.

The rail-block is to be removably secured to the rail through the medium of a substantial fastening, as a bolt 4, preferably passed through the web of the rail and through the block, being secured beyond the block by a nut, as 5.

In conjunction with the rail-block my improved adjuster comprises a tie-block 6, having a plane face 7 at the inner side and a curved face 8 at the outer side, whereby the block provides, in effect, an abutment of a height approximating the height of the rail provided with an outwardly-projecting tail-piece of reduced thickness.

The tie-block is designed to be secured to a tie in alignment with the rail-block, the securing means preferably comprising bolts 9, passed wholly through the tie and through the block at the inner end, and additional fastening means, as rail-spikes 10, driven through suitably-formed openings in the tailpiece of the block and into the tie. The bolts 9 are secured above the block by suitable nuts, as 11, and may be in any number desired, the block being appropriately formed with openings for the reception of the bolts. The spike-openings in the tailpiece of the block may, if preferred, be formed to receive the heads of the spikes, whereby, to obviate projection at this point.

An adjusting means is arranged to connect the rail-block and tie-block, preferably comprising a bolt 12 of substantial proportions, formed at one end with a head 13, designed to seat in a recess 14, formed in the outer surface of the rail-block, the recess being preferably of a size to snugly and wholly receive the head. Beyond the head the bolt 12 is threaded and designed for relatively loose passage through an opening 14, formed in the tie-block. An adjusting - nut 15, designed for operative engagement with the threaded portion of the bolt 12, is disposed on said bolt intermediate the rail-block and tie-block, being in operation arranged in contact with the inner or plane face 7 of the tie-block, whereby the rail-block, and in consequence the tread portion of the rail, may be adjusted relative to the tie-block.

A lock-nut 16 of ordinary form and for the usual purpose is preferably arranged for co-operation with the bolt 12 and the adjusting-nut. The tie-block immediately adjacent the operative position of the adjusting-nut

is preferably formed with a transversely-disposed opening 17, for the reception of a pin 18, designed to engage one of the plane faces of the adjusting-nut and prevent independent movement thereof.

The form of rail-block illustrated in Fig. 3 is primarily designed for coöperation with track-rails receiving the direct contact of the wheels. The form of block is identical with the preferred form with the exception that the lip 3 is removed, the upper surface of the block terminating in alinement with the tread-surface of the rail, thereby avoiding obstruction to the travel of the wheels.

15 In use I contemplate the application of the adjusting devices as may be necessary in the specific instance, it being understood that upon initial setting and gaging of the rail the adjusting device is secured to support the 20 rail in such position and that any tendency of the tread portion of the rail toward displacement will be resisted by the bolt 12. Furthermore, any leaning or lateral displacement of the tread portion of the rail may be 25 at once corrected and said portion restored to normal gage and position by an obvious operation of the adjusting-nut to cause a desired relative movement of the rail-block.

While preferring that a single adjusting-bolt be used, it is obvious that a number of such bolts may be utilized, if desired, and that the relative proportions and materials of the respective blocks may be varied in any degree made necessary by the specific use for 35 which the adjuster is designed.

Having thus described the invention, what is claimed as new is—

1. The combination with a railroad-rail, of means operating in alinement with the rail-tread only for adjusting the position of the tread portion of said rail.

2. The combination with a railroad-rail, of means operating in alinement with the rail-tread only for adjusting the position of the tread portion of the rail without interfering 45 with the rail-fastening means.

3. A rail-adjuster comprising a member to be secured to the rail, a relatively fixed member, and means for adjusting the rail member relative to the fixed member, said means engaging the rail-blocks at a point in alinement with the tread portion of the rail.

4. A rail-adjuster comprising a rail block shaped to conform to the sectional contour of the rail, a tie-block adapted to be secured to a tie, and means for adjusting the rail-block relative to the tie-block, said means engaging the rail-blocks at a point in alinement with the tread portion of the rail.

5. A rail-adjuster comprising a rail-block 60 adapted to be secured to a rail, a tie-block adapted to be secured to a tie, and an adjusting-bolt connecting the blocks, said bolt engaging the rail-block directly opposite the tread portion of the rail.

6. A rail-adjuster comprising a rail-block adapted to be secured to a rail, a tie-block adapted to be secured to a tie, a bolt bearing against the rail-block and passing loosely through the tie-block, and a nut coöperating with said bolt and adapted to bear against the tie-block, said bolt engaging the rail-block at a point directly opposite and in alinement with the tread portion of the rail.

7. A rail-adjuster comprising a rail-block 75 adapted to be secured to a rail, a tie-block adapted to be secured to a tie, a bolt bearing against the rail-block and passing loosely through the tie-block, a nut coöperating with said bolt and adapted to bear against the tie-block, and means to lock said nut against independent movement, said bolt being disposed in horizontal alinement with the tread portion of the rail and engaging the rail-block at a point directly opposite said 80 tread portion.

In testimony whereof I affix my signature in presence of two witnesses.

CALVIN A. JONES.
